UNITED STATES PATENT OFFICE.

GEORGE MACHLET, JR., OF ELIZABETH, NEW JERSEY.

FLUID-MIXTURE REGULATOR.

1,078,790.

Specification of Letters Patent.

Patented Nov. 18, 1913.

Original application filed August 1, 1906, Serial No. 328,697. Divided and this application filed May 12, 1908. Serial No. 432,341.

To all whom it may concern:

Be it known that I, GEORGE MACHLET, Jr., a citizen of the United States, residing in Elizabeth, in the county of Union and State of New Jersey, have invented certain new and useful Improvements in Fluid-Mixture Regulators, of which the following is a specification.

This invention relates to fluid mixing devices, such as used for instance to mix air and gas for use as fuel in furnaces.

This application is a division of my co-pending application No. 328,697, filed August 1, 1906, in which the devices shown herein are used as a part of a heat-regulating device controlled by the heat of the furnace itself. The claims in said application 328,697 relate generally to a thermo-electric generator in the furnace which operates a device to control the supply of mixed air and gas to the furnace. When the heat reaches a predetermined point, the supply of fuel is either reduced or cut off, and if the heat diminishes a trifle, the supply is renewed or increased so that the heat of the furnace is maintained with substantial uniformity at the precise point desired, which is a matter of great importance in many arts. Moreover, it frequently happens that it is desired to use the same furnace for heating the same or different metals or materials to different degrees, and accordingly I provide means for predetermining the degree of heat at which the fuel supply shall be reduced or regulated.

The heat governing apparatus includes means for regulating both the minimum and maximum supply of fuel to the furnace according to the judgment of the attendant. For some furnaces and some kinds of work there should be little variation between maximum and minimum supply, whereas in other cases the supply should at times be very great and again shut completely off. All such variations are readily secured by my invention. It is also important, especially where fuel gas and air are mixed before entering the burners in the furnace, to secure the right proportion of the gas to the air, and accordingly one feature of my invention resides in securing any desired proportion and causing such proportion to be maintained in uniformity during all fluctuations in the volume of the mixture supplied to the furnace.

In the preferred form of the invention, there is employed an apparatus for regulating or controlling the proportions of gas and air to be supplied to the furnace, and this apparatus includes a single valve having an air port and a gas port, so that when the valve is operated, both the ports are opened or closed in unison. The opening movement of the valve is limited by an adjustable stop, whereby the maximum supply of air and fuel to the furnace is determined; and another adjustable stop is provided for limiting the closing movement of said valve so that the latter may either partly close or close altogether, when the desired degree of heat of the furnace is attained, according to the character of the furnace and work in hand. A closure is provided for the gas port in said valve, which is operable independently of the air port, and the movement of said closure is directly transverse to the movement of the valve, whereby the proportion of gas may be decreased or increased independently of the opening and closing movements of the valve, thus securing during all fluctuations in the volume of mixture supplied to the furnace any desired proportions of gas and air.

Other features and advantages will hereinafter appear.

In the accompanying drawings, Figure 1 is a diagrammatic elevation of a gas furnace and an apparatus for controlling the heat thereof. Fig. 2 is a plan, and Fig. 3 a side elevation partly in section of a voltmeter forming part of a pyrometer, and also having means to control the supply of fuel to the furnace. Fig. 4 shows a vertical central section of an apparatus for controlling the proportions of gas and air. Figs. 5 and 6 are cross-sections taken through the gas compartment at the lower part of the valve seen at Fig. 4, Fig. 5 showing the gas ports open, and Fig. 6 showing them closed by means of a manually adjustable closure. Fig. 7 is a section through the mixture regulating apparatus taken at right angles to the Fig. 4 section. Fig. 8 shows an air shell or tube fixed in the upper part of the mixture regulator or proportion adjuster. Fig. 9 shows a tube which is mounted in the lower part of the mixture regulator for rotation to serve as a closure for the gas ports and the main valve. Fig. 10 shows the main valve in the regulator. Fig. 11 is a sectional view of an

air operated diaphragm for opening the valve in the regulator, and a magnetically operated valve for controlling the flow of compressed air to and away from said diaphragm. This figure illustrates the preferred means for operating the valve seen at Figs. 4 to 10. In the form seen at Fig. 4, the core of a solenoid is attached directly to said valve. Fig. 12 shows a cross-section 5 of a tube, showing vents for the exhausting of air from and admission of air to said diaphragm. Fig. 13 is an enlarged sectional view of parts seen at Fig. 11 for controlling the flow of air from the operation of said diaphragm. Fig. 14 is a plan of the apparatus 10 seen at Fig. 4.

The fuel-gas enters through a pipe 1, and the air to be mixed therewith enters through a pipe 2, the air being usually supplied 20 under pressure of a pound to several pounds to the inch. Air and gas pass separately through a proportion-adjusting apparatus 3, the gas flowing therefrom through a pipe 4, and the air through a pipe 5. The pipe 4 joins pipe 5 at the point 6, and the mixture flows through pipes 7, 8, and 9 to burners 10 which enter a furnace 11.

The apparatus 3 is in the form of a vertical pipe cast with suitable nipples to receive the pipes 1, 2, 4, 5, and divided by 30 partitions 12, 13, 14 into four chambers, namely, air inlet chamber 15, air outlet chamber 16, gas inlet chamber 17 and gas outlet chamber 18. A main valve in the 35 form of a vertical tube 19, Fig. 10, extends through said apparatus 3, said valve passing through all of said partitions and being itself divided by a partition 20 into an upper compartment 21 for air, and a lower compartment 22 for gas. The compartment 21 in the valve affords a passage for air between the inlet and outlet chambers 15 and 16. The compartment 22 forms a similar 40 passage for gas between the inlet and outlet chambers 17 and 18. Fixed in the upper part of the regulator or proportion adjuster is a tube or shell 23, Fig. 8, extending 45 through the chambers 15 and 16, and having opposite openings 24 in the former and opposite openings 25 in the latter. The 50 openings 24 register with opposite openings 26 in the valve, and the openings 25 are also juxtaposed to opposite ports 27 in the valve. It will be understood that the openings are 55 made oppositely in the valve partly for balancing the same and partly to secure ample passages for the fluids. The valve is seen closed at Fig. 4, the portions of the shell 23 indicated in dotted lines at 28, Fig. 8, serving 60 as closures for the ports 27. When the valve is fully raised, said ports register with the openings 25 in the shell 23, thereby establishing free communication between inlet and outlet pipes 2 and 5. The passages 24 and 26 are always open, the latter being of

the greater height so as to compensate for the vertical movement of the valve. In the lower end of the device is inserted another shell or tube 29 opening at its upper end into the gas inlet chamber 17, and extending 70 through the gas outlet chamber 18 in which it has opposite openings 30. The valve 19 extends also through tube 29, and fits closely in both tubes 29 and 23 while free to move up and down independently thereof. Near 75 the lower end the valve is provided with opposite ports 31, which when the valve is lifted register with the passages 30 in the tube 29. The portion of the latter indicated by dotted lines 32, Fig. 9, just below the 80 openings 30 serves as a closure for the ports 31 when the valve is dropped, Fig. 4. The valve has opposite openings 33 in the gas inlet chamber 17 corresponding with the 85 openings 26, said openings 33 being never closed. In the bottom of the valve is fitted a plug 34, and a central pipe 35 opens at one end through the plug and at the other end through the partition 20 to admit compressed air beneath the plug 34 to facilitate 90 lifting the valve. The valve is lifted by means of a rod 36, which is caught at its lower end upon a long transverse pin 37 thrust through a head 38 provided in the valve and also extending through the opposite slots 39 formed in an extension of the tube 23, which projects above chest 2. An opening 36^a in the top 36^b of head 38, prevents a vacuum forming above the head. Upon said extension are threaded nuts 41 100 and 42, one above and one below the pin 37 and engageable thereby, so that the nuts serve as adjustable stops to limit the opening and closing movements of the valve. In the Fig. 4 construction, the rod 36 constitutes 105 the core of a solenoid 43, whereby the valve 19 is lifted; but in the preferred form of the invention, Fig. 11, said rod is attached at its upper end to a flexible diaphragm 44 provided in a frame or casing 45. The upper end of the extension is screwed into said casing at 46.

Compressed air is admitted from the pipe 2 to the casing 45, that is to the lower chamber 47 of the two into which said casing is 115 divided by said diaphragm 44; the upper chamber having a vent 48. A small solenoid 49 controls the flow of compressed air from the supply pipe 2 to the chamber 47, as well as the venting of air from said chamber. 120 The core 50 of the solenoid 49 is formed at its lower end with a head which constitutes a valve 51 fitting in a stationary tube 52 and resting upon a seat 53, thereby closing said tube when the core is down. For convenience in manufacture, said tube 52 is inserted in a block or length of thick pipe 54 upon the top of which the solenoid 49 is secured, and a pipe 55 leads from said tube to the diaphragm chamber 47. When the valve 51 125 130

is lifted, the air passes up from the supply pipe 2 into the lower end of the tube 52 and through holes 56 in the side of the latter above the seat 53; but when the valve drops, 5 the tube 52 is completely closed below said hole 56, while, owing to the thinness of the valve 51, the hole 56 is left open at the top, Fig. 13, to permit air to vent from the chamber 47 through vents 57 formed in said tube, 10 the core being cut away at 58 to form a passage in the tube between the hole 56 and vent or vents 57. When the valve is raised, the head 51 is lifted up above the balanced holes 56, and no air escapes through said vents. 15 The tube 52 may continue up to form the central part of the framework of the solenoid as illustrated, and to serve as a guide for the upper end of the core.

It will be seen that when the solenoid is 20 energized, the core is raised, thus closing the tube 52 above the port 56 and leaving an open passage through said port from the compressed air supply 2 to the diaphragm chamber 47. The diaphragm is raised by 25 the air pressure, thus lifting the valve 19 and opening the ports 27 and 31, so that air and gas flow simultaneously through the chest 3. The extent to which the valve opens depends upon the adjustment of the stop 41. When 30 the magnet is deenergized, the solenoid drops and the valve 51 closes the tube 52 below the port 56 and permits the air to escape from the chamber 47 through the vents 57, whereupon the valve 19 drops until arrested by 35 the adjustable nut 42. The solenoid 49 is included in a circuit designated generally as 59 and including a battery or other source of power 60, and also including a switch 61 normally held closed by a spring 62. Said 40 circuit also includes a fixed metal bracket 63 having a lip 64 against which said switch closes. It will be seen that the electricity may flow from the battery 60 through the wire 59, then through the solenoid 49, a 45 wire 59^a, the switch 61, the bracket 63, and a wire 59^b, back to the battery, and that while the circuit is closed, the valve 51 is lifted and the regulating valve 19 is opened, so that air and fuel are supplied to the furnace. 50 The means for controlling the fuel supply also includes a thermo-electric generator 65, which is usually termed an "element," and is of well known form, and is inserted directly in the heat chamber of the furnace. This 55 generator is included in an electrical circuit 66, Fig. 1, which also includes a voltmeter or device 67 for indicating the flow of electricity in said circuit 66; said voltmeter including a movable part 68, to which is fixed 60 an index arm 69 to coöperate with a scale 70. When the element is heated, the electricity flows through the circuit 66, and the part 68 turns, thus moving the index 69 along the scale 70 to an extent to determine the degree 65 of heat in the furnace. The scale may show

either the heat of the furnace or the power of the electric current or both. I utilize the movement of said part 68 to control the valve operating circuit 59. For this purpose another circuit 71 is provided including a 70 wire 72, which is mounted on said index arm 69, and leads to a contact 73 provided upon the tip of said arm. In the path of said contact is provided a coöperating contact 74, upon the end of a metal arm 75, which is pivoted at 76 concentrically with the pin 77, upon and with which turns the member or wires 68 of the voltmeter, the pin being delicately poised upon a seat 77^a. The contact 74 may hence be set at any point on the scale 80 75 70 and rigidly secured by a nut 78. When the arm 69 swings to the right sufficiently to engage the contacts 73 and 74, the circuit 71 is closed, and the switch 61 is opened by means of a magnet 79 which is included in 85 said circuit 71. It will be seen that beginning at contact 73, the current flows along the wire 72, which at its inner end is hooked into an eye 80 formed upon a metal plate 81 secured upon the casing 82 of the voltmeter or galvanometer, said bracket being connected to a post 83 to which is secured the wire 71. The latter leads through the magnet 79, and thence through the wires 71^a and 59^b to the battery 60, the circuit including a wire 79^b connected to the conductor arm 75. The opening of the switch 61 breaks the solenoid circuit 59, thereby reducing or stopping the flow of fuel to the furnace according to the adjustment of the stop 42. 100 The wire 72 is very fine and light, and affords no appreciable resistance to the movement of the index arm 69, which is delicately poised, and which must indicate accurately the flow of electricity in the circuit 66. In 105 order to avoid injury to the fine wire 72, the coil 79^a of the magnet 79 may be made of resistance wire, so that the whole energy of the battery 60 shall not flow through said wire 72. 110 In operation it being assumed that the current is flowing through the circuit 59, valves 84 and 85 in the gas and air supply pipes 1 and 2 are opened. Compressed air flows from pipe 2 through the tubes 52 and 55 to the chamber 47, and lifts the diaphragm 44, thereby raising the valve 19 so that gas and air may flow therethrough and thence through the pipes 4, 5 and 7 to the furnace burner system 8, 9, 10, the gas being 115 ignited within the furnace. The heating of the element or thermo-electric generator 65 causes the current to traverse the circuit 66 and the member 68 to turn. The arm 75 is swung around to the point on the scale 70 120 which indicates the degree of heat which it is desired to secure and maintain in the furnace. As the furnace grows hotter, the arm 69 gradually approaches the arm 75 125 until the contact 73 engages the contact 74, 130

thereby closing the circuit 71 and breaking the circuit 59 at 61, whereupon the solenoid 49 is deenergized, its core drops, closing the passage between the compressed air supply 2 and diaphragm chamber 47, and permitting the air to vent from the latter, so that the diaphragm drops together with the valve 19, thereby partly or wholly closing the air and gas ports in the chest 3. The 10 flames in the furnace being hence reduced or extinguished, the furnace begins to cool, thus reducing the current flowing in the voltmeter, whereupon the armature 68 begins to turn back and the contacts 73 and 74 are separated and the circuit 71 broken. The 15 spring 62 closes the switch 61, thereby permitting the current to flow through the circuit 59 and the solenoid 49, so that the valve 19 is opened and air and gas again flow into the furnace, which is now sufficiently hot to ignite the gas. It will be understood however, that the stop 42 may be adjusted if desired so as to permit a little gas to flow into the furnace, so that the 20 flames may not entirely die out when valve 19 drops. After the contacts 73 and 74 engage, a very slight reduction in the heat of the furnace is sufficient to separate them, and thereby renew the supply of fuel, so that the fluctuations in the temperature of the furnace when in operation are very slight. The attendant adjusts the stops 41 and 42 to limit the opening and closing movements of the valve according to the 25 heat required and the work in hand, and also turns a hand wheel 86 to rotate the shell or sleeve 29 to open or close the gas ports 31 in the valve 19, thereby securing the desired proportions of gas and air in the mixture, which are required for different kinds of work. It will be seen that the adjustment of the sleeve 29 is at right angles or transverse to the opening or closing movements of the valve, whereby the passage at 30 31 may be enlarged or diminished transversely to alter the flow of gas, while remaining of the same height as the air port 27, so as to be co-extensively opened or closed by the movements of the valve 19. In this way, any desired proportions of 35 gas and air are constantly maintained throughout all fluctuations in the volume of the mixture delivered to the furnace. The hand wheel 86 may be provided with an index 87 to coöperate with a scale 88 to inform the attendant to what extent the passage 31 is opened or closed by the sleeve 29. The plug 89 is secured to the bottom end of the sleeve 29, and the wheel 86 is secured upon the stem of the plug by means 40 of a pin 91, which carries the index 87. The scale 88 may be formed upon a screw cap 92 threaded upon the bottom of the chest 3, and provided with a locking screw 90. The 45 judgment and experience of the attendant

will dictate the extent to which to turn the hand wheel 86 for different classes of work, and will also enable him to set the stops 41 and 42 properly; whereupon the furnace will maintain the heat at the desired point 70 for an indefinite length of time without further attention.

Variations may be resorted to within the scope of the invention. Portions of my improvements may be used without others. 75

Having thus described my invention, I claim:

1. In combination, a chest provided with an inlet and an outlet for air and also provided with an inlet and an outlet for gas, a 80 hollow valve extending through said chest and having ports between the air inlet and outlet and also having ports between the gas inlet and outlet, means for moving said valve, and means confined in said chest and having a shell form and fitting said valve and provided with ports and coöperating with said valve to control the flow of air and gas through said chest. 85

2. In combination, a chest having an air inlet chamber and a separate air outlet chamber, and a tube in communication with the inlet chamber and having ports in the outlet chamber, said chest also having a gas inlet chamber and a separate gas outlet 95 chamber, and a tube in communication with the gas inlet chamber, and having ports in the gas outlet chamber, a tubular valve extending through said tubes and fitted thereto, and divided into air and gas compartments, 100 one compartment having an opening in said air inlet chamber, and the other compartment having an opening in said gas inlet chamber, and said compartments having ports to coöperate with the ports in said 105 tubes to control the flow of gas and air through the chest, and means for operating said valve.

3. A fluid mixer comprising, in combination, a chest; a tubular valve extending 110 through said chest; means dividing said valve into uncommunicating compartments for different gases or fluids; means for operating said valve; said chest having means for separately admitting the different fluids; said valve having ports or openings and said chest also having ports or openings to coöperate with those in said valve, for regulating the volume of fluids flowing through 115 said valve; said ports and openings proportioned to permit the flow of a larger volume of one fluid than of the other, and constructed so that at the different positions to which the valve may be opened or closed, the areas of the openings formed by the adjustment of the valve will maintain substantially the same proportion one to the other; whereby a uniformity of proportions of the different fluids is secured in the mixture during 120 fluctuations of the volume thereof delivered. 125

4. In combination, a chest divided transversely into an air inlet compartment, an air outlet compartment, a gas inlet compartment, and a gas outlet compartment, a tube 5 opening into one of the air compartments and having a port in the other air compartment, a tube opening into one of the gas compartments and having a port in the other gas compartment, a tubular valve extending through said tubes and fitted there- 10 to and divided into an air compartment and a gas compartment and provided with a port in juxtaposition to said air port, and also provided with a port in juxtaposition to said 15 gas port, said tube also having in its air compartment an opening for the passage of air, and in its gas compartment an opening for the passage of gas, and means for operating said valve to open and close its 20 ports simultaneously.

5. A fluid mixer comprising, in combination, a chest, a tubular valve extending through said chest; means dividing said valve into uncommunicating compartments 25 for different gases or fluids; means for operating said valve; said chest having means for separately admitting the different fluids; said valve having ports or openings and said chest also having ports or openings to co- 30 operate with those in said valve, for regulating the volume of fluids flowing through said valve; said ports and openings proportioned to permit the flow of a larger volume of one fluid than of the other, and 35 constructed so that at the different positions to which the valve may be opened or closed, the areas of the openings formed by the adjustment of the valve will maintain substantially the same proportion one to the 40 other; whereby a uniformity of proportions of the different fluids is secured in the mixture during fluctuations of the volume thereof delivered, and adjustable means coöperating with said valve for regulating the 45 proportions of the fluids composing the mixture.

6. An apparatus for adjusting the proportions of fuel-gas and air, comprising, in combination, a chest provided with air and 50 gas admitting and delivering means, a hollow valve extending through said chest and having air-inlet and air-outlet ports, and also having gas-inlet and gas-outlet ports, and having a partition between said air 55 ports and said gas ports, means coöperating with said valve to effect corresponding variations in the volume of air and gas flowing therethrough, and means also coöperating with said valve for independently regulat- 60 ing the proportions of gas and air in the mixture delivered.

7. An apparatus for adjusting the proportions of fuel-gas and air, comprising, in combination, a chest constructed to admit 65 and deliver gas and air, a hollow valve ex-

tending through said chest and divided into air and gas compartments, ports being provided in said compartments, and means being provided for causing air and gas admitted to said chest to pass separately 70 through their respective compartments in said valve, a tube or shell fitting said valve and having a port juxtaposed to one of the ports in said valve, means for effecting relative adjustment between said valve and said shell to open or close the last mentioned valve port independently of the other valve port, so as to regulate the proportion of gas and air in the mixture delivered, and means coöperating with said valve to open or close 75 its ports simultaneously, independently of said adjustment of the proportion-regulating means.

8. In combination, a chest having air-inlet and air-outlet chambers, and also having gas-inlet and gas-outlet chambers, all of said chambers being separate, a tubular valve extending through said chambers and divided into air and gas compartments, the air compartment having a port forming part 85 of a communication between said air-inlet and said air-outlet chambers, and the gas compartment also having a port forming part of a communication between the gas-inlet and gas-outlet chambers, a closure for 90 said gas port, a closure for said air port, means for moving said valve to close both 95 its ports simultaneously, and means for adjusting the gas-port closure in a direction transverse to the movement of the valve, so 100 as to open or close the gas port and regulate the proportion of gas to air in the delivered mixture.

9. An apparatus for adjusting the proportions of fuel-gas and air, comprising, in combination, a valve having therein an air port and a gas port, said valve divided into compartments by a partition between said ports, means for moving the valve to close or open both ports together, and means adjustable in a direction transverse to the movement of the valve, for closing or opening one of said ports independently of the other thereof, so as to regulate the proportion of gas and air delivered by the apparatus. 110

10. An apparatus for adjusting the proportions of fuel-gas and air, comprising, in combination, a chest divided transversely into an air inlet chamber, an air outlet chamber, gas inlet and outlet chambers, a tubular valve extending through said chambers and divided into air and gas compartments, said valve having air and gas ports, closures in 120 said air and gas chambers for said ports, means for moving said valve endwise to close or open said ports together, and means for effecting rotative adjustment of the closure in the gas chamber, to vary the proportion of gas and air. 125

11. An apparatus for adjusting the proportions of fuel-gas and air, comprising, in combination, a chest having air inlet, air outlet, gas inlet and gas outlet chambers, 5 said chambers being separate each from the others, a tube extending from the air inlet to the air outlet chamber and opening into both, a rotatable tube extending from the gas inlet to the gas outlet chamber and opening into both, a tubular valve extending through said tubes and fitted thereto and divided into air and gas compartments having a port in each compartment, and said tubes forming closures for said ports, means 15 for moving the valve endwise to close the ports together, and means for turning the tube in the gas chamber, to close or open the port in the gas compartment of said valve, independently of the port in said air compartment so as to vary the proportion of gas 20 and air mixed.

12. An apparatus for adjusting the proportions of fuel-gas and air, comprising a chest to receive and deliver the gas and air, 25 a movable valve divided into uncommunicative gas and air compartments, having means to increase or diminish simultaneously the flow of gas and air through the chest, and for mechanically securing unvarying 30 proportions of gas and air during fluctuations in the volume delivered from said chest, and adjustable stops for limiting the stroke of the valve in both directions.

13. An apparatus for adjusting the proportions of fuel-gas and air, comprising a 35 chest, a movable valve therein and provided with means for increasing or diminishing the flow of gas and air simultaneously, and for mechanically securing unvarying 40 proportions of gas and air during fluctuations in the volume delivered from said chest, adjustable stops for limiting both opening and closing movements of said valve, and adjustable means for affecting the capacity of said 45 valve and thereby varying the proportion of gas and air delivered by the apparatus.

14. In combination, a chest divided into air inlet, air outlet, gas inlet and gas outlet 50 chambers, a tube fixed in said chest and having a part projecting therefrom and having opposite openings in said air inlet chamber, and also having opposite openings in said air outlet chamber; a tube rotatably mounted in said gas outlet chamber and communicating with said gas inlet chamber and having opposite openings in said gas outlet chamber; a manually operable device connected to said rotatable tube and provided with a scale and index, a tubular valve fitting 55 said tubes and movable endwise therein and having a partition which divides it into air and gas compartments, said valve having opposite openings into each of said chambers, its openings in the outlet chambers being closable by said tubes and being 60 65

movable into register with the tube openings in said outlet chambers, a head provided in said valve, a pin projecting from said head through a slot in said projecting portion of the first-mentioned tube, and nuts threaded 70 upon said projecting portion upon opposite sides of said pin and serving as adjustable stops for the latter.

15. In combination, a chest divided into air inlet, air outlet, gas inlet and gas outlet 75 chambers, a tube fixed in said chest and having a part projecting therefrom and having opposite openings in said air inlet chamber, and also having opposite openings in said air outlet chamber; a tube rotatably mounted 80 in said gas outlet chamber and communicating with said gas inlet chamber and having opposite openings in said gas outlet chamber; a manually operable device connected to said rotatable tube and provided 85 with a scale and index, a tubular valve fitting said tubes and movable endwise therein and having a partition which divides it into air and gas compartments, said valve having 90 opposite openings into each of said chambers, its openings in the outlet chambers being closable by said tubes and being movable into register with the tube openings in said outlet chambers, a head provided in said valve, a pin projecting from said head through a slot in said projecting portion of the first-mentioned tube, and nuts threaded 95 upon said projecting portion upon opposite sides of said pin and serving as adjustable stops for the latter; means being provided 100 for operating said valve, and the latter having at one end a plug, and also having an open tube passing through said plug and through the dividing partition within said valve, so as to balance the longitudinal fluid 105 pressure upon the valve.

16. In combination, a chest divided into air inlet, air outlet, gas inlet and gas outlet 110 chambers, a tube fixed in said chest and having a part projecting therefrom and having opposite openings in said air inlet chamber, and also having opposite openings in said air outlet chamber; a tube rotatably mounted 115 in said gas outlet chamber and communicating with said gas inlet chamber and having opposite openings in said gas outlet chamber; a manually operable device connected to said rotatable tube and provided with a scale and index, a tubular valve fitting 120 said tubes and movable endwise therein and having a partition which divides it into air and gas compartments, said valve having opposite openings into each of said chambers, its openings in the outlet chambers being closable by said tubes and being movable 125 into register with the tube openings in said outlet chambers, a head provided in said valve, a pin projecting from said head through a slot in said projecting portion of the first-mentioned tube, and nuts threaded 130

upon said projecting portion upon opposite sides of said pin and serving as adjustable stops for the latter; said projecting end of the first-mentioned tube being threaded into 5 a case or frame in which is contained a movable part connected to said valve for actuating the latter.

17. The combination of a chest element having a gas outlet port and an air outlet port, a valve device to regulate the flow of gas and air, said valve device fitting in the valve chest and movable therein to open and close the ports, a partition dividing said valve into uncommunicative gas and air 15 chambers, and manually adjustable means connected to one of said chest and valve elements to regulate the size of the opening made by moving said valve, and thereby vary the proportion of the mixture of gas 20 and air.

18. The combination of a chest having a gas outlet port and an air outlet port, a valve device to regulate the flow of gas and air, said valve device fitting in the valve 25 chest and movable therein to open and close the ports, a partition dividing said valve into uncommunicative gas and air chambers, and a member adjustable relatively to both 30 said chest and said valve device, to vary the effective opening caused by the movement of the valve for the passage of fluid, and thereby regulate the proportion of the mixture of gas and air.

19. The combination of a chest having a 35 gas outlet port and an air outlet port, a valve device to regulate the flow of gas and air, said valve device fitting in the valve chest and movable therein to open and close the ports, and a member adjustable relatively to both said chest and said valve device, to vary the proportion of the mixture of gas and air; said manually adjustable valve device in the form of a slotted cylinder.

20. In combination, a chest and a valve 45 device therein divided into uncommunicative gas and air chambers, and provided with means for increasing or diminishing the flow of gas and air simultaneously and for mechanically securing unvarying proportions of gas and air during fluctuations in the volume of the mixture delivered from 50 said chest, and manually adjustable means for affecting the capacity of said valve device and thereby varying the proportions of gas and air in the delivered mixture.

21. In combination, a chest and a valve device therein provided with means for increasing or diminishing the flow of gas and air simultaneously and for mechanically securing unvarying proportions of gas and 60 air during the fluctuations in the volume of the mixture delivered from said chest, said

chest having ports, and a manually adjustable closure for one of said ports, said closure adjustable in a direction transverse to 65 the movement of said valve device, for varying the proportions of air and gas in the delivered mixture.

22. A fluid mixture regulator comprising a chest having a plurality of inlets, one for 70 each of the fluids to be mixed, valve means movable to control concomitantly the quantity of each fluid passing through said chest, so that the quantities will be according to a predetermined ratio, said valve means having 75 passages therein for said fluids, and divided by a partition into uncommunicative gas and air chambers and proportionating means for varying said ratio by varying the effective capacity of certain of said passages 80 relative to certain others of said passages, whereby the quantity permitted to pass by a given movement of said valve means for certain of said fluids will be changed, and for certain others will remain constant. 85

23. A fluid mixture regulator comprising a chest having inlets and outlets, means for permitting passage of a plurality of fluids to be mixed, a tubular valve having passages for permitting flow of the fluids there- 90 through, said valve being movable to regulate the volumes of fluids passing there- through, and a member movable relatively to said valve, to vary the size of one of the 95 passages therein, to determine the effective capacity of such passage in said valve for a given movement of said valve.

24. An apparatus for adjusting the proportions of a plurality of fluids to be mixed having means for admitting and delivering 100 the several fluids, means, including a valve, for controlling the volume delivered by the apparatus, said volume-controlling means including a device for securing mechanically unvarying proportions of the several 105 fluids during fluctuations in the volume delivered, and adjustable means for regulating the proportions of the several fluids in the mixture; said valve divided into uncommunicative gas and air compartments. 110

25. A fluid mixture regulator comprising a chest having inlet and outlet openings therein, a tubular valve having passages therein separated from each other, one passage for each of the fluids to be combined in 115 the mixture, said tubular valve being movable axially to vary concomitantly the quantity of all of the fluids passing through said passages in said valve.
